CLAIM

The ornamental design for an eight conductor modular plug, substantially as shown and described.

DESCRIPTION

FIG. 1 is a top perspective view of the eight conductor modular plug showing our new design;

FIG. 2 is a side elevational view thereof;

FIG. 3 is a bottom plan view thereof;

FIG. 4 is a rear elevational view thereof;

FIG. 5 is a front elevational view thereof; and

FIG. 6 is a bottom perspective view thereof.
